2,187,516

PROCESS FOR SEALING COLLAPSIBLE TUBES

Mervil Hallead, Cincinnati, Ohio, assignor to The
Karl Kiefer Machine Company, Cincinnati,
Ohio, a corporation of Ohio

Application June 30, 1936, Serial No. 88,185

7 Claims. (Cl. 113—112)

My invention relates to the sealing of collapsible tubes or like containers and is a departure from the methods and machines set forth in the co-pending application in the name of Paul R. Fechheimer, Serial No. 710,824, filed February 12, 1934, now Patent No. 2,102,840, issued December 21, 1937, and in the co-pending application of Paul R. Fechheimer and Mervil Hallead, Serial No. 88,186, filed June 30, 1936, now Patent No. 2,141,241, issued December 27, 1938. The fundamental object of my invention is the provision of a method and means for obtaining an improved weld, and in particular a constructionally neater though positive closure, and this and the other objects of my invention which will be set forth hereinafter or will be apparent to one skilled in the art upon reading these specifications I accomplish by that certain construction and arrangement of parts and in that process of which I shall now describe an exemplary embodiment.

Reference is now made to the drawings wherein Fig. 1 is a side elevation of a sealing assembly. Fig. 2 is a top plan view thereof.

Fig. 3 is a sectional view taken along the lines 3—3 of Fig. 1.

Figs. 4 to 7 inclusive show various stages in the operation of the sealing mechanism.

Fig. 8 shows an electrically operated sealing element.

Fig. 9 is a perspective view of the sealed end of a collapsible tube.

Briefly in the practice of my invention I clamp the end of a collapsible tube, the end being pinched together or fish-tailed between holding members. Next I bring down upon the end of the tube a heating element which fuses the metal of the end of the tube. Next two molding members are brought in from the sides against the softened metal, consolidating the weld and giving a sealed tube characterized by a neat bead at the sealed end. All of these steps can be carried on by automatic machinery in rapid succession and I shall herein describe an exemplary embodiment of such machinery, it being understood that modifications can be made therein without departing from my invention.

Ordinarily, though not necessarily, the sealing of the tubes will be carried on in connection with the operation of filling them, and the filling and sealing mechanisms may form part of the same machine. After the tubes are filled, the ends thereof will be pinched or fish-tailed, and I have shown mechanism for this purpose as a part of my disclosure herein. In the practice of the proc-

ess herein set forth it is quite essential that the ends of the tubes to be sealed be substantially of the same height and come substantially the same distance above the clamping jaws in the sealing unit. While it is not necessary in all instances to do this, I have found it commercially advisable to shear the ends of the tubes after pinching them, and to this end I have shown an appropriate unit operating in timed sequence with the other portions of my mechanism.

Coming now to a detailed description of my exemplary embodiment, I have shown in Figures 1 and 2 a machine portion comprising a conveyor 1 having at intervals holders 2 for collapsible tubes indicated at 4. The construction of the frame of the machine may be any desired, and has not been illustrated, excepting for a bed plate 5, on or in which the conveyor moves. A divided sub-base or support 6 for the various units may be mounted above the bed plate by means of posts 7. The sub-base is divided to permit the upper portions of the tubes to project through it. On the sub-base are mounted the pinching, shearing, and sealing units in the order named, though the number of these units, and the number of assemblies of them per machine may be multiplied at will, as will be obvious. The two sections of the sub-base 6 will be separated at the entering end of the device sufficiently to accept the body of an uncollapsed tube as shown at 8 in Figure 2. Beyond the pinching unit the spacing between the sub-base sections may be narrowed down as shown so as to accept only the pinched ends of the tubes.

The pinching unit comprises a pair of plates 9 and 10, slidably mounted on the sub-base sections by means of bracket members 11 and 12 or otherwise as desired. These plates have turned-up abutment portions 13 and 14 the function of which is to pinch or fish-tail the tube ends when the plates are brought together. The operation of the pinching plates is most conveniently accomplished by providing each plate with a spring 15 or 16 operating against abutments 17 or 18 on the sub-base, and of sufficient strength to cause the plates to pinch the tube ends. The plates are then held apart or allowed to come together through the action of cam members presently to be described, upon arms 19 and 20 attached to the plates.

All of the units mounted on the sub-base have parts which are to be brought together against the tube ends, and it is convenient to provide for all of the units and common operating means. This means comprises a shaft 21 journaled in 55

suitable brackets 22 and 23 near the ends of the sub-base. The shaft may be connected to another shaft 24 at right angles thereto by means of the bevel gear arrangement 25, and this shaft 5 in turn connected to another shaft 26 by means of bevel gears 27. Power is applied to the shaft 26 in any way desired, and the shaft 26 will be connected into the power drive for the conveyor 1, in such a way that the various units on the 10 sub-base operate in timed relation to the arrival of the tubes thereat as determined by the movements of the conveyor. A pair of cams 28 and 29 may be mounted on the shaft 21 to actuate the arms 19 and 20. Thus upon the arrival of 15 a tube between the plates 9 and 10, the cams permit the plates to come together, pinching the tube as indicated at 30.

The shearing unit comprises an anvil plate 31 and a shear 32, which may similarly be slidably 20 mounted in brackets on the sub-base, and which may similarly also be spring actuated as at 33 and 34. Preferably a clamping plate 35 is mounted on the under side of the shear plate 32, slidably, and held thereto by bolts 36, engaging in 25 slots in the plate 35. The plate 35 will be urged forwardly of the shear blade by means of a spring connecting it with the shear blade underneath, and therefore not shown in the drawings. The shearing mechanism has actuating 30 arms 37 and 38 which engage cams 39 and 40 on the shaft 21. In operation the plate portions 31 and 35 come together against the pinched or fish-tailed end of the tube which projects slightly therebeyond. Immediately 35 thereafter the shear plate 32 with its knife edge slides over the plates 35 and 31 sufficiently to shear off the projecting end of the tube.

The tube then moves on to a sealing device, a 40 cross section of which is clearly shown in Fig. 3. The sealing device comprises a pair of mold plates 41 and 42, slidably mounted in studs or the like 45 on the sub-base 6. The plates have abutments 44 and 45 between which and abutments 46 and 47 on the sub-base, there are compression springs 45 48 and 49. The plates thus are adapted to operate in the same way as the plates of the pinching and shearing mechanisms. Here, as in those mechanisms, I have found it preferable to thread bolts 50 and 51 into the abutments on the plates 50 so that the heads of these bolts will impinge 55 against the abutments 46 and 47 on the sub-base, to prevent over-running. The bolts are of course, adjustable and may be locked with lock nuts as shown. The plates are provided with 60 operating arms 52 and 53, which are operated by cam members 54 and 55, on the shaft 21.

In the case of the sealing mechanism however, the plates 41 and 42 just described, are 65 molding members adapted to come against the end of the tube when the metal therein is molten, to consolidate the weld and to form a bead therein. As a consequence of this, these metal plates are provided with mold faces indicated at 56. It is desired to clamp the tube ends at the sealing 70 station before these mold members come in contact with them. A suitable construction for this is shown in Fig. 3, where a plate of hard and preferably insulating substance 57 is shown attached by a screw 58 to one of the sub-base sections. This is a stationary clamping member. A movable clamping member 59 may be slidably attached as by means of screws 60, to the plate 41, and urged forwardly of said plate by means of a compression spring 61 operating against 75 abutment means 62 on the plate 41.

While I have shown the plate 57 attached to the sub-base, it can if desired, be mounted on the plate 42 in a way similar to the mounting of the plate 59 on the plate 41.

In the construction shown, it is desirable to 5 clamp the tube end between the insulating blocks 57 and 59 as a first step in the welding procedure, afterward fusing the metal and then bringing the mold face 56 of the plates 41 and 42 against the fused metal. Consequently provision 10 is made for two components of motion in the plate 41. The first component is sufficient only to permit the plate 59 to clamp the tube against the plate 57. The second component, together with a simultaneously occurring motion of the 15 plate 42, brings the mold face against the fused metal. The cam 55 is therefore appropriately shaped to accomplish this dual motion in the cycle.

A fusing means is provided and preferably 20 comprises an electrical heating element 63 of tubular shape, and comprising as shown in Fig. 8, a resistance heater 64. The heating element 63 is mounted on suitable supporting means indicated generally at 65, and supported upon a 25 pair of arms 66 and 67 pivoted to brackets 68 and 69 on the sub-base. There is provided a compression spring 70, bearing against at least one of these arms and adjustable by means of a bolt 61. The spring tends to urge the heating element 30 and its mounting means upwardly. One or more cams 72 mounted on the shaft 21 and bearing against suitable abutments on the mounting means 65 for the heating element, serve to bring the heating element down against the work in 35 timed relationship.

The various steps of the sealing procedure are indicated in Figs. 4 to 7 inclusive. In Fig. 4 the pinched and sheared tube end has been brought between the insulating plates 57 and 59. The 40 plates 42 and 41 are in interspaced relationship and the heating element 63 does not contact the work. As a next step, and automatic consequence of the operation of the cams, the plate 41 is moved to the left in Fig. 5, sufficiently to 45 allow the plate 59 to clamp the tube end against the plate 57. The tube end is now held in position for welding.

As a next step, the condition shown in Fig. 6 is arrived at. The tube end is seal clamped between the insulative members 57 and 59 and the heating element 63, has been brought down against the tube end fusing the metal as at 73. The plates 57 and 59 not only serve to position the tube end but also by their insulative character serve to prevent spread of the fusion of the metal. Thus the fused portion of the metal lies substantially wholly above the tops of the plates 57 and 59. A material which I have found entirely suitable for the plates 57 and 59, is a 60 hard, dense, electrically insulative material obtainable on the open market and known as Transite, having comparatively high heat insulative properties. The final stage of the welding operation is illustrated in Fig. 7. The plates 65 41 and 42 have been brought together so that their mold faces 56 contact the softened body of metal 73, contact the weld and form a neat bead therein. I have found it advisable to bring the plates 41 and 42 together with some little 70 force to achieve the desired contacting action, especially if, as is usual, the heating element 63 is raised slightly just before the plates 41 and 42 are brought together. However it is possible and within the scope of my invention, to raise 75

the heating element 63, soon after the molding plates have been brought together.

The resultant sealed tube is shown in Fig. 9, as having a pinched or fish-tailed end 74, and a neat bead 73a molded from the softened metal 73 as shown in Fig. 6.

Modifications may be made in my invention without departing from the spirit thereof.

Having thus described my invention, what I claim as new and desire to secure by Letters Patent is:

1. A process of sealing collapsible tubes which comprises as sequential steps, pinching a tube end to bring wall portions into juxtaposition, shearing said tube end to bring said wall portions to a given height, clamping said wall portions between insulating material so that they project therebeyond, softening the projecting wall portions by means of a heated member, applying molding pressure thereto by means of molding members, and cooling the softened metal.

2. A process of sealing collapsible metal tubes by welding or fusion, which comprises bringing the end wall portions of said tubes into juxtaposed position and clamping said portions between heat insulative clamping members so that portions of said walls project therebeyond, melting the said projecting portions, and thereafter while said portions are in molten condition, bringing thereagainst from each side, molding members having high heat conductivity, whereby the molten metal is immediately chilled and hardened.

3. A process as set forth in claim 2 wherein the fusion of said projecting portions is accomplished by means simultaneously effective along the line of said projecting portions.

4. A process of sealing collapsible metal tubes by welding or fusion, which comprises bringing end wall portions of said tubes into juxtaposition, trimming said wall portions whereby to expose freshly cut metal surfaces thereat, and immedi-

ately thereafter sealing said wall portions together by contacting said cut surfaces with a tool for applying heat to fuse the metal thereof.

5. A process of sealing collapsible metal tubes by welding or fusion, which comprises bringing end wall portions of said tubes into juxtaposition, clamping the juxtaposed walls with portions extending beyond the clamp, shearing off said projecting portions, again clamping said walls with a portion extending beyond the clamp, using for this purpose clamping means of insulative substance, and fusing said end wall portions together by applying sufficient heat to melt the metal thereof, and immediately thereafter bringing against the melted portions of said walls heat conductive molding means whereby to seal said portions.

6. A process of sealing collapsible tubes by welding or fusion, which comprises bringing end wall portions of said tubes into juxtaposition, clamping the juxtaposed walls with portions extending beyond the clamp, shearing off said projecting portions whereby to expose freshly cut metal surfaces, immediately thereafter again clamping said walls with a portion extending beyond the clamp, using for this purpose clamping means of insulative substance, and immediately fusing said end wall portions together by means of a tool for applying sufficient heat to melt the metal thereof, said tool being brought into contact with said freshly cut metal surfaces.

7. A process of sealing collapsible tubes by welding or fusion, which comprises bringing end wall portions of said tubes into juxtaposition, trimming said end wall portions so as to expose freshly cut metal ends for welding and so as to enforce close contact between said ends, and immediately thereafter fusing said ends together by contacting said ends with a means for applying a fusing heat thereto.

MERVIL HALLEAD. 40
